(57) **CLAIM**

The ornamental design for a heat pad controller, as shown and described.

DESCRIPTION

FIG. 1 is a front, top right perspective view of a first embodiment of a heat pad controller showing my new design therefor;

FIG. 2 is a bottom, rear left perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken lines show portions of the heat pad controller that form no part of the claimed design.
